ATTORNEYS

UNITED STATES PATENT OFFICE.

BEVERLY POWELL HERNDON, OF FLORENCE, ARIZONA TERRITORY.

DESIGN FOR A TWINE-CUTTER.

SPECIFICATION forming part of Design No. 34,236, dated **March 19, 1901.**

Application filed February 23, 1901. Serial No. 48,627. Term of patent 7 years.

To all whom it may concern:

Be it known that I, BEVERLY POWELL HERNDON, a citizen of the United States, residing at Florence, in the county of Pinal and Territory of Arizona, have invented and produced a new and original Design for Twine-Cutters, of which the following is a specification, reference being had to the accompanying drawings, forming part thereof.

Figure 1 is a side or edge view, and Fig. 2 an end view, of a twine-cutter, showing my new design.

The leading feature of the device is the form of the body or main portion, composed

of a ring *a*, and an arm *b*, extending laterally from the ring and having a reverse curve or *cyma recta*. A block or bar *c* is arranged transversely at the outer and lower side of the ring *a* and provided with a notch, across which extends a sharp-edged plate *d*.

What I claim is—

The design for a twine-cutter, substantially as shown and described.

BEVERLY POWELL HERNDON.
